US00D517008S

(12) **United States Design Patent** (10) Patent No.: **US D517,008 S**
Yasuda et al. (45) Date of Patent: **** Mar. 14, 2006**

(54) **ENGINE-DRIVEN GENERATOR**

(75) Inventors: **Hitoshi Yasuda**, Kawagoe (JP); **Satoshi Kojima**, Kawagoe (JP)

(73) Assignee: **Denyo Kabushiki Kaisha**, Tokyo-To (JP)

(**) Term: **14 Years**

(21) Appl. No.: **29/230,721**

(22) Filed: **May 26, 2005**
